(57) **CLAIM**

The ornamental design for a toothbrush bristle arrangement as shown and described.

DESCRIPTION

FIG. 1 is a front perspective view of a toothbrush bristle arrangement showing my new design;

FIG. 2 is a front elevational view of FIG. 1;

FIG. 3 is a rear elevational view of FIG. 1;

FIG. 4 is a left side elevational view of FIG. 1;

FIG. 5 is a right side elevational view of FIG. 1;

FIG. 6 is a top plan view of FIG. 1;

FIG. 7 is a bottom plan view of FIG. 1;

FIG. 8 is a partially enlarged view of portion “8” taken from FIG. 4; and,

FIG. 9 is a partially enlarged view of portion “9” taken from FIG. 2.

The dash-dash lines shown in the drawings depict portions of the toothbrush and form no part of the claimed design. The dot-dash broken lines shown in FIGS. 2, 4, 8, and 9 are for the purpose of depicting enlarged view indicators, and form no part of the claimed design.
